UNITED STATES PATENT OFFICE.

ROBERT R. ZELL, OF BALTIMORE, MARYLAND, ASSIGNOR TO THE CAMPBELL & ZELL COMPANY, OF SAME PLACE.

WATER-TUBE BOILER.

SPECIFICATION forming part of Letters Patent No. 469,810, dated March 1, 1892.

Application filed November 19, 1891. Serial No. 412,365. (No model.)

To all whom it may concern:

Be it known that I, ROBERT R. ZELL, of Baltimore, in the State of Maryland, have invented a new and useful Improvement in 5 Water-Tube Boilers, of which the following, taken in connection with the accompanying drawings, is a specification.

This invention has for its object to produce an improved water-tube boiler which is simple in construction, efficient in operation, and one in which the circulation is continuous, thereby avoiding the burning out of the parts due to the deposit of sediment on the inside of the parts exposed to the direct action of the 10 products of combustion, and, further, a boiler having a large heating-surface, whereby the circulation is increased and the steam rapidly generated.

My invention consists of certain novel features of construction, combination of parts, and arrangement of co-operating parts, all as hereinafter described, and particularly set forth in the claims.

In the accompanying drawings, which illustrate my invention, Figure 1 is a side elevation of the boiler with the side furnace-wall omitted, so as to show the arrangement of the connections of the various parts of the boiler. Fig. 2 is a rear elevation of the boiler.

Referring to the views of the drawings, it will be seen that within the furnace-walls A' there is arranged a water tubular boiler consisting of three cylindrical water-drums A, B, and C, arranged sidewise to the furnace. The drum B is connected to the drum A by means of the curved inclined tubes d, and the drum A is connected with the drum C by means of the curved inclined tubes g. The tubes d and g are arranged in rows across the furnace and 30 in each row are parallel to each other, and in each row are located above the spaces between the tubes in the row beneath, as shown in Fig. 2, thereby forming a staggered arrangement of the tubes, by means of which a large heating-surface is exposed to the fire, which is broken up by the staggered arrangement of the tubes. From the said drum C several pipes J extend downward to the drum B. The steam-drum D is connected to the drum A 45 and the drum C by the pipes F and E, respectively. The drums A and C are supported

on horizontal wrought-iron beams E', the drum A by a rest F' and rollers h h, and the drum C on the saddle I. The drum B is supported on the saddle H, resting upon suitable 55 brick-work in the bottom of the furnace.

The furnace is of the ordinary construction and is provided with a grate c, resting upon suitable supports c² in the front furnace-wall A', and a bridge-wall b. c' represents the 60 the opening through which the fuel is introduced to the grate c. Deflectors a a of fire-brick are arranged above the upper series of tubes d and g and serve to deflect the products of combustion around and through the 65 tubes, compelling the products of combustion to take a circuitous route, thereby exposing a large surface to said products of combustion, by means of which the water is rapidly heated, a perfect circulation is produced, and 70 steam is rapidly generated.

The boiler, as above described, can be made entirely of steel, and will have a very small number of openings and joints, and is well adapted for high pressures. The tubes d and 75 g can be tapped or otherwise secured to the respective water-drums A, B, and C.

K K' represent doors, by means of which access is had to the interior of the furnace, for the purpose of cleaning out or for repairs. 80

By means of the rollers h h, having suitable supports, the expansion and contraction of the various parts of the boiler is provided for without breakage or loosening of any of the parts, as the rollers permit a longitudinal 85 movement forward or backward, due either to expansion or contraction.

The water-drums A, B, and C and the steam and water drum D are provided with the usual hand-holes and hand-hole covers L'. 90 The boiler is provided with the usual fire-box and ash-pit doors and the usual gage-cocks, equalizing-pipes, and safety-valves.

The operation of the boiler is as follows: The feed-water is introduced into the drum 95 C by means of the pipe M, provided with a valve m', and being heavier than the heated water in the boiler descends through the tubes J into the lower cylindrical boiler-drum B, which acts as a water-leg and mud-drum or 100 separator. The tubes d enter the sides of the said water-drums radially or at a line drawn

through their centers. The circulation of the water will be across the drum B, as shown by the arrows, and upward through the inclined tubes *d* into the water-drum A, and from said 5 water-drum the water can return either through the inclined tube *g* to the drum C to mix with the incoming feed-water, or may ascend through the pipes F into the steam and water drum D, the water in the said steam-water drum descending by means of the pipes E, where it mixes with the feed-water introduced into the drum C by the pipe M, provided with the valve *m'*, and the circulation of the water continues in this manner around 10 and through the various drums and tubes. The sediment in the water is deposited in the bottom of the drum B, from which it may be blown off through the pipe L, having the valve *l*, as shown in Fig. 2, or cleaned out from time 15 to time. The facilities for cleaning the boiler are excellent, as by the construction above described the deposit takes place in the drum B, from which it can be easily cleaned out. The construction of the boiler also admits 20 of many boilers being set up in a continuous battery, as they can be cleaned from the ends and top instead of the sides, as with the other water-tube boilers now in use.

By closing the valve *m'* in the pipe M and 30 opening the valves *m* in the pipe M' and valve *l* in the pipe L the boiler may be blown off.

I do not intend to limit myself to the exact construction shown, as the same may be varied without departing from the spirit of my invention.

Having thus ascertained the nature and set forth the construction of my invention, what I claim as new, and desire to secure by Letters Patent of the United States, is—

40 1. In a water-tube boiler, the combination of a mud-drum, cylindrical water-drums at the front and rear of the furnace arranged above said mud-drum, with one series of curved inclined water-tubes connecting said mud-drum and the front water-drum and another series of curved inclined water-tubes connecting the front and rear water-drums, a feed-pipe entering the rear water-drum, and a steam and water drum connected to the said 45 water-drums, said water-tubes entering the drums at a line drawn through their centers, substantially as set forth.

50 2. In a water-tube boiler, the combination of a mud-drum, cylindrical water-drums at the front and rear of the furnace arranged above said mud-drum, with two series of curved water-tubes arranged across the furnace in rows and communicating at one end with the front water-drum and at the other 55 end communicating, respectively, with the mud-drum and the rear water-drum, pipes connecting the rear water-drum and the mud-drum, a feed-water pipe entering the said rear water-drum, and a steam and water drum 60 in communication with said water-drums, the

said water-tubes entering the drums at a line drawn through their centers, substantially as set forth.

3. In a water-tube boiler, the combination of a mud-drum, two water-drums arranged 70 above said mud-drum, with two series of water-tubes communicating at one end with one of the water-drums and at the other end communicating, respectively, with the mud-drum and the other water-drum, a steam and water 75 drum in communication with the said water-drums, and a yielding support for the water-drum with which all the tubes communicate for the purpose of allowing a longitudinal movement due to contraction or expansion, 80 substantially as set forth.

4. In a water-tube boiler, the combination of a mud-drum, front and rear water-drums arranged above said mud-drum, with two series of staggered water-tubes communicating 85 at one end with the front water-drum and at the other end communicating, respectively, with the mud-drum and the rear water-drum, a feed-water pipe entering the said rear water-drum, a steam and water drum in communication with said water-drums, and deflectors arranged above the upper layer of each 90 series of water-tubes in opposite directions, so as to cause a circuitous travel to the products of combustion, substantially as set forth. 95

5. In a water-tube boiler, the combination of a mud-drum, front and rear water-drums arranged above said mud-drum, with one series of curved inclined staggered water-tubes connecting said mud-drum and the front water-drum and another series of curved inclined staggered water-tubes connecting the front and rear water-drums, a feed-water pipe entering the said rear water-drum, a steam and water drum in communication with said 105 water-drums, and deflectors arranged above the upper layer of each series of water-tubes in opposite directions, so as to cause a circuitous travel to the products of combustion, substantially as set forth. 110

6. In a water-tube boiler, the combination of a mud-drum, water-drums arranged above said mud-drum, with two series of water-tubes communicating at one end with one of the water-drums and at the other end communicating, respectively, with the mud-drum and the other water-drum, a steam and water drum in communication with the water-drums, a yielding support for the water-drum with which all the tubes communicate, and supporting-beams for the water-drums, substantially as set forth. 115

In testimony whereof I have signed my name to this specification, in the presence of two subscribing witnesses, on this 16th day of November, A. D. 1891.

ROBERT R. ZELL.
